(57) **CLAIM**

The ornamental design for a display panel of a programmed computer system with an animated graphical user interface, as shown and described.

DESCRIPTION

FIG. 1 is a first view of a first embodiment of a display panel of a programmed computer system with an animated graphical user interface;

FIG. 2 is a second view thereof;

FIG. 3 is a third view thereof;

FIG. 4 is a fourth view thereof;

FIG. 5 is a fifth view thereof;

FIG. 6 is a first view of a second embodiment of a display panel of a programmed computer system with an animated graphical user interface;

FIG. 7 is a second view thereof;

FIG. 8 is a third view thereof;

FIG. 9 is a fourth view thereof; and,

FIG. 10 is a fifth view thereof.

The broken line showing a display panel forms no part of the claimed design. The broken lines showing portions of the animated graphical user interface form no part of the claimed design

The appearance of the image transitions sequentially between the images shown in FIGS. 1-5 and 6-10, respectively. The process or period in which an image transitions to another forms no part of the claimed design.
